COAL COKING AND BURNING MAGAZINE
STOVEJohn C. Miles, Urbana, Ill., assignor to Board of
Trustees, University of Illinois, Urbana, Ill.

Application January 31, 1946, Serial No. 644,563

7 Claims. (Cl. 126—73)

1

This invention relates to a coal stove or the like for heating buildings.

All bituminous coal contains large amounts of volatile matter which is not burned completely in the ordinary stove or furnace and is given off in the form of smoke. This not only wastes much of the fuel value of the coal but also results in a dirty atmosphere. Various methods have been proposed for burning the combustible vapors. Most of these methods, however, are not adaptable to simple stoves for the heating of residences.

I have invented a light-weight, inexpensive stove which uses the downdraft principle of burning to consume the smoke. This new stove requires a minimum of attention and can be easily regulated so that the heat given off can be controlled. The new stove provides for a storage space which can be filled with coal and will then require no attention for considerable periods of time.

With the new coal stove it is now possible to heat small homes efficiently and at extremely low cost. All the combustible matter of the fuel is burned and there is very little or no smoke given off at any time.

The invention will be described as related to the embodiment of the same set out in the accompanying drawings. Of the drawings Fig. 1 is a partial vertical section taken substantially through the center of the stove; Fig. 2 is a horizontal section taken along line 2—2 of Fig. 1; Fig. 3 is a horizontal section taken along line 3—3 of Fig. 1; Fig. 4 is a horizontal section taken along line 4—4 of Fig. 1; and Fig. 5 is a horizontal section taken along line 5—5 of Fig. 1.

The coal stove shown in the accompanying drawings comprises a shell 10, a base 11, and an exhaust pipe 12 for the escape of burned gases. The shell 10 is of substantially cylindrical shape except for a flat rear portion 13 inclined downwardly and inwardly. This flat rear portion extends from near the top to approximately the mid-portion of the shell.

On the inside of the shell there is located a flat plate 14 arranged substantially parallel to and spaced from the flat rear portion 13 of the shell. This plate 14 is supported on four posts 15 and has its bottom end 16 extending into the stove. The top edge of the plate 14 is spaced from the top portion 17 of the shell.

At the top of the shell 10 there is located a radiator 18 communicating with the exhaust pipe 12. This radiator is separated from the firebox 19 that is located in front of the flat plate 14.

2

Immediately beneath the lower edge of the flat plate 14 there is located a flat grate 20 formed of three substantially rectangular grate bars 21, 22, and 23. This grate defines the bottom of the firebox.

At the front of the stove there is located a combustion chamber 24 formed of refractory elements 25 against the shell 10 and a second set of refractory elements 26 spaced from the first set 10 25. The top of the combustion chamber 24 communicates with the radiator 18, while the bottom of the combustion chamber communicates with the firebox 19. The bottom entrance to the combustion chamber 24 is formed by an inclined shoulder 27 of refractory material extending beyond the inner edge of the combustion chamber and into the firebox. The inclined shoulder 27 forms a constricted entrance 28 to the combustion chamber 24.

Secondary air is admitted upwardly to the combustion chamber 24 through an air passageway 29 at the front of the stove and beneath the inclined shoulder 27. This secondary air passageway is formed by refractory or metal elements 30 held in spaced relationship from the shell 10. The top of the refractory elements 30 as shown is spaced from the shoulder 27 and inclined inwardly and upwardly to form an air opening 31.

The bottom portion of the flat plate 14 contains a number of holes or perforations 32. These holes extend upwardly to a point substantially even with the bottom of the refractory elements 26 forming the combustion chamber 24. The rear inclined portion 13 of the shell 10 contains air ports 32a and 32b with both ports covered by an adjustable damper 33. The air ports 32a and 32b are formed by a division strip 14a extending across the flat plate 14. Air enters the port 32a and flows upwardly over the upper end of the flat plate 14 and down along the flat plate into the under-grate portion 34 of the stove. The air flows through port 32b, down along plate 14, through the holes 32, up through the grates 20, and up through the secondary air passageway 29 and openings 31 and 28 into the combustion chamber 24. When the furnace is in operation and filled with coal the firebox 19 will be divided into a coke-burning zone 35 extending from the grates to the entrance 28 to the combustion chamber 24,

45 a coking zone 36 above the coke-burning zone 35, and an uncoked coal zone 37 above the coking zone 36. Air enters the coke-burning zone 35 through the grates 20 around the bottom portion of the inclined plate 14 and through the lower holes 32. Air enters the coking zone 36 through

the upper holes 32. Air enters the uncoked coal zone 37 around the upper edge of the flat plate 14. The top front portion 17 of the shell 10 adjacent this upper edge is provided with a downwardly extending flange 38 to direct the air in a generally downward direction through the uncoked coal zone 37.

At the top of the stove and beside the radiator 18 there is located an opening 39 for the introduction of coal into the firebox 19. This opening 39 is normally closed by a hinged door 40 that opens toward the radiator 18. This hinged door may be opened by means of a handle 41. Adjacent the opening 39 is a second opening 42 between the firebox 19 and the radiator 18. This second opening 42 is normally kept closed by a sliding door 43 held in side brackets 44. The two doors 40 and 43 are connected by a bar 45 hingedly mounted at one end on the first door 40 and also hingedly mounted at the other end on the sliding door 43. With this construction the two doors are opened and closed substantially simultaneously.

Each of the grate bars 21, 22, and 23 which define the bottom of the firebox are hingedly mounted at points beneath their mid-sections. The first grate bar 21 at the front of the firebox is provided with a relatively short downwardly extending bar 46. The second grate bar 22 is provided with a similar bar 47 of appreciably greater length, and the third grate bar 23 is provided with a similar bar 48 of still greater length. The lower ends of each of these bars, 46, 47, and 48 are rotatably connected by an inclined bar 49. With this arrangement the grates are shaken by moving the inclined bar 49 back and forth, by means of any desired mechanism. This movement rotates the grate bars 21, 22, and 23, with the grate bar 21 being rotated through the greatest arc, the second grate bar 22 being rotated through the next greatest arc, and the third grate bar 23 through the smallest arc. This construction is important because the greatest burning rate occurs at the front of the stove, and the grate bar 21 underneath this portion is given the greatest agitation when the grates are shaken. As shown in the drawings the middle grate bar 22 is turned by a handle 59 extending through the shell 10, and this turns the other grate bars 21 and 23.

The under-grate portion of the stove is provided with an ash removal door 51 at the front or back thereof. The radiator 18 has a top opening 52 that is used for clean-out purposes, and this opening is normally kept closed by means of a weighted cover 53.

When the furnace is in operation air enters through the air ports 32a and 32b. The air from port 32a is directed down through the uncoked coal zone 37. The air from port 32b is directed laterally into the coking zone 38; another portion of this air is directed laterally into the coke-burning zone 35; a portion of the air is directed upwardly into the coke-burning zone 35; and a final portion of the air is directed up through the secondary air passageway 29 around the shoulder 27, and through the constricted opening 28 into the combustion chamber 24. The burning gases ordinarily extend through the combustion chamber 24 and into the radiator 18. In this chamber all of the volatile combustible products are consumed, leaving only the gases from the combustion to be exhausted out the pipe 12.

Having described my invention as related to the embodiment shown in the accompanying

drawings, it is my intention that the invention be not limited by the details of description unless otherwise specified but rather be construed broadly within its spirit and scope as set out in the accompanying claims.

I claim:

1. A coal stove comprising a shell having a front wall inclined downwardly and inwardly; a plate arranged substantially parallel to said front wall for at least the greater part of its length and spaced therefrom; a firebox behind said plate divided into a coke-burning zone at the bottom thereof, a coking zone above said coke-burning zone and an uncoked coal zone adjacent the top portion of said plate; said plate having perforations therein communicating only with the coke-burning zone and the coking zone; means forming an air port through said shell opposite said plate and above the coke-burning zone; a grate beneath the lower edge of said plate and forming the lower boundary for said coke-burning zone; means forming a combustion chamber above and laterally displaced from the coke-burning zone; means for directing a portion of the air from said air ports downwardly into the uncoked coal zone; means for directing a portion of the air through said perforations; means for directing a portion of the air upwardly into the coke-burning zone; and means for directing a portion of air upwardly as secondary air into the combustion chamber.

2. The coal stove of claim 1 wherein the upper edge of said plate is separated from the top portion of the shell to provide an air opening into the top of the uncoked coal zone.

3. The coal stove of claim 1 wherein there is provided a constricted neck portion of diminishing cross-section at the bottom entrance to the combustion chamber through which the secondary air enters.

4. The coal stove of claim 1 wherein the top portion of the shell contains a radiator separated from the firebox with the top of the combustion chamber opening into said radiator on one side thereof and a stack for burned gases communicating with an opposite side thereof.

5. The coal stove of claim 1 wherein the top of the firebox contains means forming an opening for the introduction of coal normally closed by a door, and the top portion of the shell contains a radiator separated from the firebox with the top of the combustion chamber opening into said radiator on one side thereof and a stack for burned gases communicating with an opposite side thereof, said radiator having means forming an opening communicating with the firebox and normally closed by a door, said opening between the radiator and the firebox being located beneath the stack.

6. In a coal stove and the like having a firebox formed with a coke-burning zone, the combination comprising: means forming a combustion chamber above one side of the coke-burning zone and communicating therewith at the bottom of the combustion chamber, a baffle at one side of the coke-burning zone and beneath the combustion chamber with the baffle being spaced from the adjacent side of the stove and the bottom of the combustion chamber to form an air passageway, and the top edge of the baffle adjacent said side of the stove being sloped upwardly and inwardly, and a second baffle having a portion projecting from the said side of the stove into the space between the first baffle and the bottom of the combustion chamber and spaced

from each, said second baffle having an upwardly and outwardly sloped top surface leading to the bottom entrance of the combustion chamber, the said sloped top of the first baffle and projecting portion of the second baffle forming gradually diminishing constricted air entrances to the coke-burning zone and to the bottom of the combustion chamber.

7. The coal stove of claim 6 wherein the projecting portion of the second baffle extends beyond the inner surface of the first baffle and the inner side of the combustion chamber.
